UNITED STATES PATENT OFFICE.

FRANK S. WOODHEAD, OF BRIDGEPORT, CONNECTICUT, ASSIGNOR TO THE SINGER MANUFACTURING COMPANY, A CORPORATION OF NEW JERSEY.

FEEDING MECHANISM FOR SEWING-MACHINES.

1,020,068.

Specification of Letters Patent. Patented Mar. 12, 1912.

Application filed April 29, 1909. Serial No. 493,017.

To all whom it may concern:

Be it known that I, FRANK S. WOODHEAD, a citizen of the United States, residing at Bridgeport, in the county of Fairfield and State of Connecticut, have invented certain new and useful Improvements in Feeding Mechanism for Sewing-Machines, of which the following is a specification, reference being had therein to the accompanying drawings.

This invention relates to improvements in feeding mechanisms for sewing machines, and has for its object to provide means for uniformly advancing materials of varying texture and thickness to the action of the stitch-forming mechanism, and is particularly adapted for use in connection with attaching collarettes or elastic bindings to knitted fabrics.

Owing to the difficulty experienced in producing uniform feed movements of the adjoining portions of material when stitching together elastic or knitted fabrics, it has been customary to employ what is commercially termed "differential feeding mechanism" which, generally considered, comprises two independently actuated feed-dogs capable of independent control with respect to the amplitude of their feed movements. The present construction effects the desired result by providing a feeding mechanism which comprises a single feed-dog having multiple feeding surfaces, in connection with multiple cloth-pressers which are adjustably secured relatively to each other, thus providing means whereby the thicker or seamed portions of the material will be advanced in a manner common to sewing machines generally, while the thinner or body portions will be acted upon by the adjustably-secured cloth-pressers which, in the present instance, are constructed to yield to the action of the feed-dog independently of their vertical movements with the presser-bar, to facilitate the feeding of substantially heavily ribbed knitted goods.

Referring to the accompanying drawings, in the several figures of which like parts are similarly designated, Figure 1 is a view in perspective of the improved mechanism, together with an edge-folding guide and a portion of the cloth or bed plate of the sewing machine. Figs. 2, 3 and 4 are perspective views of the cloth-pressers, throat-plate, and feed-dog, respectively. Fig. 5 is a per-

spective view of one form of product for which the improved mechanism was designed.

1 represents the cloth or bed plate of the sewing machine, 2 the front slide-plate, 3 an edge-folding guide secured by screw 4 to the plate 1, 5 the presser-bar to the lower end of which is secured, by screw 6, the threaded end only being shown, the cloth-presser bracket 7 which has formed integral with it the main or permanent cloth-presser 8, 9 the needle-bar, and 10 the needle carried by said bar. To the bracket 7 are secured, by screws 11 and 12, the respective spring cloth-pressers 13 and 14.

15 represents the usual needle opening formed in the cloth-presser 8.

The feed-dog 16, comprising the integrally-formed feed-points or feeding surfaces 17, 18, 19 and 20, is mounted and operated in a manner common to sewing machines employing four-motion feeding mechanisms. The throat-plate 21 is secured in the usual manner to the plate 1 and is provided with suitable openings for accommodating the needle and feed-dog in their actuations. Said throat-plate is also provided with a raised portion, the upper surface of which occupies a plane substantially in line with the median horizontal plane of the delivery end 22 of the edge-folding guide 3.

In applying the improved mechanism to the class of productions represented by Fig. 5, the thicker or seam portion 23 of the material is fed beneath the cloth-presser 8 by the action of the feed-points 18 and 19, the two-ply portion of the binding material 24 is advanced under the spring cloth-presser 14 by the action of the feed-point 20, and the main or body portion of the material is advanced by the coaction of the spring cloth-presser 13 and feed-point 17. Thus it will be seen that an independent feed control is provided for each different thickness of material.

Claims:—

1. A feeding mechanism for sewing machines comprising a throat-plate, a feed-dog, a presser-bar, and a plurality of cloth-pressers carried by said presser-bar, said cloth-pressers being relatively adjustable to normally hold their effective surfaces in different horizontal planes, the central of said cloth-pressers comprising a rigid element, and the cloth-pressers arranged on opposite

sides of said central cloth-presser being flexible to yield vertically for the purpose described.

2. A feeding mechanism for sewing machines comprising a throat-plate, a feed-dog, a presser-bar, and a plurality of cloth-pressers carrier by said presser-bar, said cloth-pressers being relatively adjustable to normally hold their effective surfaces in 10 different horizontal planes, the central of said cloth-pressers comprising a rigid element of substantially the combined width of the cloth-pressers arranged on opposite sides of said central cloth-presser, said oppositely arranged cloth-pressers being flexible to yield vertically for the purpose described.
3. A feeding mechanism for sewing machines comprising a throat-plate, a feed-dog, a presser-bar, a presser-bar bracket and a plurality of cloth-pressers carried by said bracket, said cloth-pressers being relatively adjustable to normally hold their effective surfaces in different horizontal planes, the 20 central of said cloth-pressers comprising a rigid element and the cloth-pressers ar-

ranged on opposite sides of said central cloth-presser being flexible to yield vertically for the purpose described.

4. A feeding mechanism for sewing machines comprising a throat-plate having its upper surface stepped to better accommodate the feeding of superposed plies from the delivery end of a folding guide to the action of the stitch-forming mechanism, a 30 feed-dog, a presser-bar and a plurality of cloth-pressers carried by said presser-bar, said cloth-pressers being relatively adjustable to normally hold their effective surfaces in different horizontal planes, the central of said cloth-pressers comprising a rigid element and the cloth-pressers arranged on opposite sides of said central cloth-presser being flexible to yield vertically for the purpose described. 40

In testimony whereof, I have signed my name to this specification, in the presence of two subscribing witnesses.

FRANK S. WOODHEAD.
